MULTIPLE IRONING MACHINE

John H. Leef, Minneapolis, Minn.

Original application May 1, 1948, Serial No. 24,571, now Patent No. 2,556,477, dated June 12, 1951. Divided and this application February 15, 1950, Serial No. 144,341

21 Claims. (Cl. 38—5)

1

My present invention relates to improvements in ironing or pressing mechanisms of the kind embodying a plurality of individual ironing or pressing units or machines mounted in spaced relation on a common supporting structure for common movements with respect to the operator's station; this application being filed as a division in part of my United States Letters Patent Number 2,556,477.

An important object of my invention is the provision of ironing mechanism as set forth having means for automatically operating the presser shoes of the ironers at predetermined intervals during their travel with respect to the operator's station.

Another object of my invention is the provision of means for automatically locking the shoes of the several ironers in a closed garment-ironing position when said ironers are out of registration with the operator's station.

Another object of my invention is the provision of means for automatically locking the shoes of the several ironers in open position when said ironers are in substantial registration with the operator's station.

Another object of my invention is the provision of novel mechanism for preventing accidental movements of said shoes toward or away from each other during the travel thereof with respect to the operator's station.

A still further object of my invention is the provision of cam-operated means for accomplishing the above objects.

Still another object of my invention is the provision of ironer mechanism as set forth having a cam engageable with mechanism for operating the presser shoes and in which said cam is shiftable into and out of the path of travel of said mechanism.

Another object of my invention is the provision of ironing mechanism as set forth having power-operated mechanism for moving the presser shoes to and away from pressing engagement, control means for the power-operated means, cam-operated mechanism for operating said control means, and means for preventing accidental operation of the operating mechanism for the control means.

Another object of my invention is the provision of ironer mechanism having fluid pressure-operated means for moving the presser shoes into and out of pressing engagement, a control valve for said fluid pressure-operated means, and cam-operated mechanism for operating said control valve.

2

Another object of my invention is the provision of cam mechanism as set forth, which is relatively inexpensive to produce, rugged in construction, and efficient and durable in use.

5 Other highly important objects and advantages of my invention will become apparent from the following detailed specification, appended claims, and attached drawings.

Referring to the drawings, wherein like characters indicate like parts throughout the several views:

Fig. 1 is a plan illustrating a group of ironers mounted on a turntable in accordance with my invention and showing a preferred embodiment thereof;

Fig. 2 is an enlarged fragmentary view, partly in side elevation and partly in section, taken substantially on the line 2—2 of Fig. 1;

Fig. 3 is an enlarged fragmentary section taken 10 on the line 3—3 of Fig. 2;

Fig. 4 is a fragmentary view partly in section and partly in side elevation, taken on the line 4—4 of Fig. 2;

Fig. 5 is a view corresponding to Fig. 4 but 15 showing a different position of some of the parts;

Fig. 6 is a view in plan of one of the cam elements of my invention;

Fig. 7 is a view corresponding to Fig. 2 but 20 illustrating a modified form of presser shoe-operating mechanism; and

Fig. 8 is a diagram of a fluid pressure system 25 for operating the machine of Fig. 7.

Referring in greater detail to the structure of 30 Figs. 1—6 inclusive, the numeral 1 indicates, in its entirety, a supporting structure in the nature of a turntable comprising an annular supporting plate 2 secured to a concentric annular hub 3 by means of a plurality of radial arms 4. The plate 35 2 is reinforced by concentric annular flanges 5 and 6, the latter being in the nature of a structural angle iron welded to the plate 2 at its peripheral edge portion. Depending spaced flanges 7 form bearing brackets journaling 40 wheels 8 for rotation upon an endless circular track 9.

Mounted fast on the annular supporting plate 45 2 is a plurality of circumferentially-spaced pressing or ironing devices 10, each having a relatively stationary pressing shoe 11 and a relatively movable pressing shoe 12. The fixed elements 11 50 are mounted on circumferentially-spaced pedestal-like bases 13. Each shoe 12 is provided with arms 14, rigidly secured thereto, projecting radially inwardly of the turntable and pivoted at

their intermediate portions to their respective bases 13, as indicated at 15. The ironers 10 have identical linkage for moving their respective movable shoes 12 from the closed position shown to a spread-apart open position and vice versa. For the sake of brevity, but one of the operating linkage units or mechanisms will be described.

An adjustable link 16 is pivotally secured to the radially inner end of the arm 14 as indicated at 17. The lower end of the link 16 is provided with a roller not shown but which is adapted to ride in a cam slot 18 in a vertical bracket 19 rigidly secured to the annular plate 2. Also pivotally secured to the lower end of the link 16 is the outer end of a piston rod or plunger 20, which is equipped with a piston not shown but contained within a fluid pressure-operated cylinder 21 hingedly secured, as indicated at 22, to the frame base or pedestal 13. A second fluid pressure-operated cylinder 23 is pivotally secured to the base frame 13, as indicated at 24, and is provided with a piston-equipped plunger rod 25 which has pivotal engagement with the arm 14 intermediate its pivot 15 and its inner end, as indicated at 26. The movable shoe 12 is biased away from engagement with the relatively fixed shoe 11 by means of a coil tension spring 27 anchored at one end to the turntable 1 and at its other end to the intermediate portion of the link 16.

Ironing machines of this character are generally constructed to provide a padded ironing shoe and a metallic faced heated ironing shoe. In this case, the stationary shoe 11 is padded and preferably provided with a cloth cover while the relatively movable shoe 12 is hollow and is heated by suitable means such as live steam. For introducing the heating medium to the hollow movable shoe 12, I provide an inlet pipe 28, the lower end of which is rotatably connected to the upper portion of a steam manifold 29 through a packing gland or the like 30. The upper or input portion 31 of the manifold 29 is divided from the lower or exhaust portion 32 thereof. A plurality of inlet tubes 33 lead one each from the input chamber 31 of the manifold 29 to one of the movable shoes 12. The shoes 12 are each provided with drain pipes or tubes 34 that are connected to the lower exhaust portion 32 of the manifold 29. The inlet tubes 33 and the drain tubes 34, being flexible in part, do not interfere with the freedom of movement of the relatively movable shoes 12. Condensate from the shoes 12 passes through the tubes 34 into the exhaust chamber 32 from whence it is removed through a drain pipe 35 connected to the manifold 29 by a packing gland 36 and a fitting 37. The packing gland connections 30 and 36 permit rotation of the manifold 29 while the inlet pipe 28 and the drain 35 remain in a stationary condition.

Fluid under pressure is supplied to the several ironers for moving the relatively movable shoes 12 from a source of fluid supply not shown through a pipe 38 which extends upwardly through the fitting 37, the packing gland 36, and the manifold exhaust chamber 32 by means of a suitable joint or slip connection 39. The pipe 38 extends radially outwardly of the manifold 29 and branches off to the several ironers on the turntable 1, as indicated at 40. A branch conduit 41 extends from the connection 40 to a control valve 42. From thence, conduit means 43 and 44 lead to the respective cylinders 21 and 23. It will be seen, by reference to Fig. 3, that the conduit means 43 and 44 are coupled to the valve 42

by a T fitting 45 and that the valve 42 has a port 46 open to atmosphere.

Continuous and uninterrupted rotary movement at a relatively slow speed is imparted to the turntable 1 by a motor 47 which drives a shaft 48 through connections, not shown but contained within a gear box 49. A sprocket wheel 50 is secured fast to the shaft 48 and positively drives a link chain 51 which extends about and is carried within a channel 52 formed by the outer peripheral portion of annular plate 2 and the flange 6. The chain 51 is maintained in frictional driving contact with the flange 6 by an idler pulley 53 journaled to one arm of a bell-crank 54 that is pivoted to a stationary quadrant 55. Pin and socket connections 56 of a conventional design are utilized to maintain the idler 53 in a position to tighten the link chain 51. Obviously, moving the bell-crank 54 in a counter-clockwise direction with respect to Fig. 1 will loosen the link chain 51 in the channel 52. This arrangement provides an inexpensive but satisfactory drive for the turntable 1. It will be observed that the turntable rotates in a clockwise direction with respect to and as shown by arrows in Fig. 1.

I provide means adjacent the track 9 and to one side of an operator's station x for automatically and successively manipulating the control valve 42 operatively associated with each ironer 10 upon rotation of the turntable 1. This control valve operating or tripping means is in the nature of a relatively stationary cam 57 elongated in the general direction of the track 9. The cam 57 lies in the path of travel of a plurality of pairs of trip members in the nature of cam followers, one pair thereof associated with each ironer 10. One of the cam followers is in the nature of a roller 58 and is journaled at one end of a bell-crank 59 pivoted at its intermediate portion to a lever 60, as indicated at 61. The lever 60 is mounted intermediate its ends, as indicated at 62, for swinging movements in a vertical plane, to a bracket 63 depending from the annular plate 2. A second cam follower or roller 64 is journaled to one end of the lever 60 and the pivotal connection 61 between the bell-crank 59 and the lever 60 is located intermediate the cam follower 64 and the pivotal connection 62 of the lever 60 to the bracket 63. At its forward end, the lever 60 is pivotally connected to a rigid link 65 which extends upwardly through a suitable opening in the annular plate 2 and is pivotally connected at its upper end to a crank arm 66 rigidly secured to a rotary plug or valve member 67 in the control valve 42. The cam followers 58 and 64 are movable by engagement with the cam 57 from inoperative positions, as indicated in Fig. 4, to operative positions, as shown by full lines in Fig. 5. It will be noted that the cam followers 58 and 64 are spaced apart a distance less than the length of cam 57, so that during rotation of the turntable 1, both cam followers are at a given time coincidentally in their operative positions. The end of the bell-crank 59 opposite the cam follower 58 is notched, as indicated at 68, whereby to have latching engagement with a lug 69 on the bracket 63 when the cam followers 58 and 64 are in their inoperative positions. Raising of the cam follower 58 causes the notched end 68 of the bell-crank 59 to move away from the lug 69 to permit raising of the cam follower 64, as indicated in Figs. 4 and 5. The cam follower or roller 64 cannot be elevated from its position of Fig. 4 unless the cam follower 58 is in an elevated position because of the engagement of the

notched portion of the bell-crank 59 with the lug 69 when the follower 58 is in its lower position. Hence, if any foreign material, such as a block of wood or the like, happens to be inadvertently placed under the turntable in the path of travel of the cam followers 58 and 64, the first cam follower 58 may be elevated thereby and thereafter permitted to drop to its lower bell-crank latched position before the second cam follower 64 is engaged by said foreign material. Thus, when the follower 64 comes into contact with the foreign material, the lever 60 is held against upward movement by engagement of the notch 68 with the lug 69, and the foreign material will be pushed out of the way by the follower 64, or the resistance set up by the foreign material will be sufficient to stop rotation of the turntable 1. In any event, with this arrangement, the mechanism cannot be operated to cause the movable shoe 12 to be moved in a predetermined direction with respect to the stationary shoe 11 unless both of the followers 58 and 64 are in their elevated operative positions imparted thereto by engagement with the cam 57.

The above described cam-operated mechanism operates the control valve 42 to cause the several ironers 10 to be successively opened when approaching the operator's station x. I provide means for successively closing the several ironers 10 upon departure thereof from the operator's station, said means being in the nature of a relatively stationary cam 70 circumferentially spaced from the cam 57 sufficiently to be located at the opposite side of the operator's station x. The cam 70 is also in spaced relationship to the cam 57 in a direction radially of the turntable 1 and lies in the path of travel of a plurality of pairs of cam followers and valve-operating mechanism associated with the several ironers 10, in the same manner as the above described cam followers and control valve-operating linkage. The pairs of cam followers adapted to engage the cam 70 each comprise a first cam follower 71 and a second cam follower 72 spaced therefrom in the direction of travel thereof. The cam follower or roller 71 is journaled to one end of a bell-crank 73 which is pivotally secured at its intermediate portion to a lever 74, as indicated at 75. The lever 74 is pivotally mounted intermediate its ends as at 76 to a depending bracket 77 on the turntable 1. Each cam follower 72 is journaled to one end of its cooperating lever 74 outwardly of the pivotal connection 75, said pivotal connection 75 being intermediate the roller 72 and the pivotal connection 76 of the lever 74 to its cooperating bracket 77. The free end of the bell-crank 73 is notched, as indicated at 78, to engage a stop lug 79 on the bracket 77. This arrangement is identical to the construction of the bell-crank 59 with its notch 68 and the notch-engaged lug 69 on the bracket 63 of each ironer. At its opposite end, the lever 74 is pivotally connected to the lower end of a rigid link 80 which projects upwardly through the annular plate 2 and has its upper end pivotally secured to a crank arm 81 at the opposite end of the valve member 67 and extending in a direction diametrically opposite to the crank arm 66 thereof. It will be noted that as each pair of cam followers 71 and 72 are moved to their operative positions by the cam 70, the rigid link connections therebetween and their cooperating valve 42 and between the valve 42 and the cam followers 58 and 64 associated therewith, cause said cam followers 58 and 64 to be moved to their inoperative positions, as indicated in Fig. 4. Conversely, movement of

the cam followers 58 and 64, of each pair, imparted thereto by the cam 57 from their inoperative to their operative position, causes corresponding movement of the cam followers 71 and 72 from their operative to their inoperative positions. It will be noted that cam-imparted movement of the cam followers 71 and 72 from their inoperative to their operative positions moves the valve member 67 to a position, permitting flow of fluid under pressure from the conduit 41 to the valve 42, through the conduits 43 and 44 to their respective cylinders 21 and 23, whereby to close the press 10 associated therewith. On the other hand, movement of the cam followers 58 and 64, associated with each ironer 10, imparted thereto by the cam 57, causes the valve member 67 associated therewith to be moved to a position whereby the supply of fluid under pressure is cut off from the conduit 41 and the cylinders 21 and 23 opened to atmosphere through the respective conduits 43 and 44 and the valve 42, permitting retractive movements of the plunger rods 20 and 25 and opening of the press under bias of the spring 27.

The cam 70 is shiftable in a direction radially of the turntable 1 into and out of the path of travel of the several pairs of cam followers 71 and 72. The cam 70 is mounted in a pair of spaced guides 82 which are suitably secured to the floor. The cam 70 is further provided with a radially inwardly extending arm 83, to the inner end of which is pivotally secured one end of a lever 84 which is pivotally mounted intermediate its ends to the floor, as indicated at 85. The opposite end of the lever 84 is pivotally secured to one end of a shifter handle 86 which extends generally radially outwardly beyond the periphery of the turntable 1 where it may be grasped by the operator. Suitable means, such as a pin 87, may be inserted into either one of a pair of spaced apertures 88 in the floor radially outwardly of the turntable 1. By reference to Fig. 6, it will be noted that but one of the apertures 88 is shown, the other being assumed to underlie the pin 87. The full lines of Fig. 6 illustrate the cam track in position to engage the several pairs of cam followers 71 and 72, whereas the dotted lines indicate the position assumed by the cam 70 when it is moved to its inoperative position radially outwardly of the path of travel of the said cam followers 71 and 72.

In operation, as the turntable 1 rotates about its axis, the several ironers 10 mounted thereon are successively moved to their open position as a result of movement of the several pairs of cam followers 58 and 64 imparted thereto by the cam 57, from their inoperative to their operative positions, and consequent operation of control valve 42. As each ironer 10 passes the operator's station x, the operator places a garment to be ironed upon the relatively stationary shoe 11. As each ironer 10 leaves the operator's station x, the cam 70 engages the cam followers 71 and 72, moving the same from their inoperative to their operative positions, consequent operation of the valve 42 thereby causing the ironers 10 to be successively closed to pressing engagement with the material to be ironed. Speed of continuous and uninterrupted rotation of the turntable 1 is such that one revolution thereof is sufficient to complete an ironing operation. Hence, as each ironer having a garment between the ironing shoes thereof approaches the operator's station x, the said ironer will be caused to open to permit shifting of the garment thereon 70 for ironing a different portion of the garment

or for removal of the garment from the ironer and the placing of a different garment to be ironed thereupon, after which the ironer will again be closed and the ironing cycle repeated. When it is desired to shut down the machine for a given period of time, it is necessary that the several ironers 10 be maintained in an open position to prevent scorching of the cloth covering and padding of the stationary shoes 11 by their cooperating heated movable shoes 12, 10. This is accomplished by merely manipulating the handle 86 to move the cam 70 from its full line position of Fig. 2 to its radially outward dotted line position thereof out of the path of travel of the several pairs of cam followers 11, 15 and 72. Then, as each ironer 10 approaches the operator's station, it is caused to open by engagement of its cam followers 58 and 64 with the cam 57, the shoes remaining open thereafter. One complete revolution of the turntable 4 is sufficient to cause all of the ironers mounted thereon to be opened, after which the motor 47 may be shut off.

In the modified arrangement shown in Figs. 7 and 8, the turntable, garment ironer, fluid pressure-operated means for opening and closing the garment ironers, and means for supplying steam to the ironers and fluid under pressure to the operating means therefor, are identical to the corresponding portions illustrated in Figs. 1 to 6, inclusive, as are the cam followers thereof, and carry the same numbers with prime marks ('') added. In the modified arrangement, however, the branch connection 41' extends to a control or reversing valve 89. From thence, conduits 43' and 44' extend to the cylinders 21' and 23', respectively. The valve 89 has a port open to atmosphere through a short conduit 90 and a muffler 91. The valve 89 is operated by a fluid pressure-operated reversing motor comprising axially aligned fluid pressure cylinders 92 and 93 provided with pistons and having a common piston rod 94. A collar 95 fast on the piston rod 94 has pin and slot connection 96 with an arm 97 which is connected to and projects radially outwardly from a rotary valve member 98 in the valve 89. The rotary member 98 is chambered to permit fluid under pressure to enter the cylinders 21' and 23' in one position thereof, and in another position thereof, to allow fluid to escape from the cylinders 21' and 23' to atmosphere through the conduit 90 and the muffler 91. Fluid under pressure is supplied to the cylinders 92 and 93 from the conduit 41' by a branch conduit 99 which leads to a pair of pilot valves 100 and 101. Pipes 102 and 103 lead respectively from the pilot valves 100 and 101 to respective cylinders 92 and 93. The pilot valves 100 and 101 are of the well known type having opposed valve seats and valve elements therefor, the valve elements each carried by a reciprocal stem 104, 60, yieldingly biased in one direction by a spring 105, see particularly Fig. 8. The pilot valves are further provided with exhaust passages 106 leading to atmosphere. Movement of the stem 104 of the pilot valve 100 against bias of the spring 105 allows fluid under pressure to flow through the conduits 99 and 102 into cylinders 92, 65, whereby to move the collar 95 on the piston rod 94 from the left to the right with respect to Fig. 8. This will rotate the member 98 of the valve 89 to a position to permit fluid to escape from the cylinders 21' and 23' to atmosphere through the muffler 91. Simultaneous movement of the pistons carried by the cylinders 92 and 70, 75,

93 from the left to the right with respect to Fig. 8, causes fluid contained within the cylinder 93 to be passed through the conduit 103 to atmosphere through the exhaust passage 106 in the pilot valve 101. Similarly, movement of the stem 104 of the pilot valve 101 against bias of the spring 105 will allow fluid under pressure to flow through the conduit 99, valve 101, and conduit 103 into the cylinder 93, whereby to move the piston-equipped rod 94 and collar 95 from the right to the left, with respect to Fig. 8, thereby causing rotation of the member 98 to allow passage of fluid under pressure to the cylinders 21' and 23'. Consequent outward movement of the piston rods 20' and 25' moves the arm 14' and shoe 12' toward pressing engagement with the relatively fixed shoe 11'. As is the case of the structure shown in Figs. 1 to 6, initial closing movement of the shoe 12' is caused by outward movement of the piston rod 25' and final pressing action is effected by outward movement of the piston rod 20' during the final movement of the shoe 12' toward the shoe 11'. This final locking pressure between the shoes 11' and 12' is made effective by engagement of the roller, not shown, but at the pivotal connection between the link 16' and the piston rod 20', with the extreme upper end of the cam slot 18'. Generally, in machines of this type, the reciprocal valve stems 104 are moved by button-equipped push rods 107, one of which is shown, pivotally connected to the outer ends of bell-cranks 108 that are pivoted to the base 13', as indicated at 109. For operating the pilot valves 100 and 101, I provide rigid links 110 and 111 which are pivotally secured one each at their upper ends to one of the bell-cranks 108 and at their lower ends to one each of a pair of bell-cranks 112 and 113, respectively. The opposite end of the bell-crank 112 is pivotally secured to the upper end of the rigid link 65', whereas the opposite end of the bell-crank 113 is pivotally secured to the upper end of the rigid link 80'. As shown, the bell-cranks 112 and 113 are pivoted at their intermediate portions to brackets 114 secured to the base or mounting structure 13'. The cam 70' is movable radially out of the path of travel of the cam followers 71' and 72' whereby to render said cam followers inoperative to close the ironers 10'.

Operation of the ironer of Figs. 7 and 8 is identical to those of Figs. 1 to 6, inclusive, except that the control valve 89 for the cylinders 21' and 23' is operated by fluid pressure-operated cylinders 92 and 93, as compared to direct operation by rigid links 65 and 80, as in the case of the structure of Figs. 1 to 6, inclusive. This arrangement and operation is fully disclosed in my pending application above identified.

It is understood that the ironer disclosed in Figs. 7 and 8 in itself is old in the art. However, I have found that by mounting ironers of this type on the turntable, as shown, and automatically controlling the movements of the movable shoes with respect to the relatively fixed shoes thereof, I have been able to effect a great saving in time and labor in ironing of various garments on production scale.

While I have shown and described a commercial embodiment and a single modified arrangement of my novel garment ironer, it will be understood that the same is capable of further modification without departure from the spirit and scope of the invention as defined in the claims.

What I claim is:

1. In an ironing machine of the class described, an endless track, a supporting structure mounted and guided for traveling movements about said endless track, driving mechanism for imparting movements to said supporting structure about said track, a normally open garment ironer mounted on said supporting structure and comprising cooperating pressing shoes mounted for relative movement between a normally open position and a closed position, a relatively stationary cam mounted adjacent said track and elongated generally in the direction thereof, first and second cam followers carried by the supporting structure for cam-imparted movements with respect thereto from normal inoperative positions to operative positions, said cam followers being spaced apart in the direction of travel of the supporting structure a distance less than the length of the cam and being located to be successively intercepted and moved by the cam from inoperative to operative positions, and ironer shoe-operating mechanism mounted on the supporting structure, said operating mechanism comprising said cam followers and being responsive to coincidental cam-imparted movements of the cam followers from inoperative to operative positions, but to neither thereof singularly, to move said movable shoe in one direction.

2. In a device of the class described, an endless track, a garment ironer movably mounted on said track, mechanism for imparting continuous and uninterrupted movement to said ironer about said track, said garment ironer comprising a fixed shoe and a cooperating shoe movable between an open and closed position relative thereto, a first cam follower mounted for movements with the ironer about said track, operating mechanism for the relatively movable shoe operatively associated with said cam follower and responsive to movements thereof to move the movable shoe with relation to its cooperating fixed shoe, an elongated relatively fixed cam element mounted adjacent the track and in the path of travel of said first cam follower for engagement by and movement of the first cam follower, a second cam follower operatively associated with the first cam follower and mounted for cooperation with said cam element and also mounted for movements with the ironer about the track being located in forwardly-spaced relation to the first cam follower a distance less than the length of the elongated cam element, and mechanism under control of the second cam follower and extending to the mechanism under control of the first cam follower for rendering the latter inoperative to cause movement of the movable shoe when the first cam follower is disengaged from the cam.

3. In an ironing machine of the class described, an endless circular track, a supporting structure mounted and guided for traveling movements about said track, a driving mechanism for imparting continuous and uninterrupted movements to said supporting structure about said track, a garment ironer mounted on said supporting structure, said garment ironer comprising a fixed shoe and a cooperating shoe movable between an open and closed position relative thereto, first and second cam followers carried by the supporting structure for movements with respect thereto from normal inoperative positions to operative positions, a relatively stationary cam mounted adjacent said track and elongated generally in the direction thereof, said stationary

cam lying in the path of travel of said cam followers whereby to successively intercept and move said cam followers from inoperative to operative positions, said cam followers being spaced apart in the direction of travel of said supporting structure a distance less than the length of the cam, and ironer shoe operating mechanism for moving the movable shoe in one direction with respect to said stationary shoe and including said cam followers, said operating mechanism being responsive to coincidental cam-imparted movements of the cam followers from inoperative to operative positions, but to neither thereof singularly, to move said movable shoe in one direction.

4. In an ironing machine of the class described, an endless circular track, a turntable rotatably mounted on said track, mechanism for imparting continuous and uninterrupted movement of said turntable on said track, a plurality of normally open garment ironers mounted on said turntable in circumferentially spaced relationship, each of said garment ironers comprising cooperating pressing shoes mounted for relative movement between a normally open position and a closed position, a relatively stationary cam mounted adjacent said track and elongated generally in the direction thereof, first and second cam followers operatively associated with each of said ironers and carried by said turntable for cam-imparted movements with respect thereto from normal inoperative positions to operative positions, the cam followers associated with each of said ironers being spaced apart in the direction of rotary movement of the turntable a distance less than the length of the cam and being located to be successively intercepted and moved by the cam from inoperative to operative positions, and ironer shoe-operating mechanisms mounted on each of said ironers, said operating mechanisms each comprising one each of said first and second cam followers and being responsive to coincidental cam-imparted movements of the cam followers from inoperative to operative positions, but to neither thereof singularly, to successively close each of said ironers.

5. In an ironing machine of the class described, an endless circular track, a supporting structure mounted and guided for traveling movements about said track, a driving mechanism for imparting continuous and uninterrupted movement to said supporting structure about said track, a garment ironer mounted on said supporting structure, said garment ironer comprising a fixed shoe and a cooperating shoe movable between an open and closed position relative thereto, spaced pairs of cam followers carried by the supporting structure for movements with respect thereto from normal inoperative positions to operative positions, a pair of relatively stationary cams mounted adjacent said track and spaced apart in the direction thereof, said cams being elongated generally in the direction of said track and laterally offset from each other, each thereof lying in the path of travel of a different pair of said cam followers whereby to intercept and move said cam followers from inoperative to operative positions, the cam followers of each pair being spaced apart in the direction of travel of said supporting structure a distance less than the length of its cooperating cam, and ironer shoe-operating mechanism including said pairs of cam followers, said operating mechanism being responsive to coincidental cam-imparted movements of both cam followers of one of said pairs

from inoperative to operative positions, but to neither thereof singularly, to move said movable shoe in one direction, said operating mechanism being responsive to coincidental cam-imparted movements of both cam followers of the other of said pairs from inoperative to operative positions, but to neither thereof singularly, to move said movable shoe in the opposite direction.

6. The structure defined in claim 1 in which said ironer shoe operating mechanism further includes a lever carrying said second cam follower, an arm carrying said first follower, said arm being pivotally mounted on said lever, and latch means associated with said arm and operative to lock said lever against movement toward a cam follower operative position.

7. The structure defined in claim 1 in which said ironer shoe operating mechanism further includes a lever carrying said second cam follower at one of its ends and pivotally mounted intermediate its ends to said frame structure, and a bell crank carrying said first cam follower at one of its ends and having its intermediate portion pivotally mounted to said lever intermediate the pivotal connection thereof to said frame and said second cam follower, the opposite end of said bell crank having latching engagement with a portion of said supporting structure when said cam followers are in their inoperative positions and movable out of said latching engagement therewith upon movement of said first cam follower to its operative position by said relatively stationary cam.

8. The structure defined in claim 4 in which said ironer shoe operating mechanism further includes a lever carrying said second cam follower, an arm carrying said first cam follower, said arm being pivotally mounted on said lever, and latch means associated with said arm and operative to lock said lever against movement toward a cam follower operative position.

9. The structure defined in claim 1 in further combination with means mounting said relatively stationary cam for shifting movements into and out of cam-engaging relationship with said cam followers, and means for shifting said cam.

10. In an ironer of the class described, an endless circular track, a turntable rotatably mounted on said track, mechanism for imparting continuous and uninterrupted movement to said turntable on said track, a plurality of garment ironers mounted in circumferentially spaced relationship on said turntable, each of said garment ironers comprising a stationary shoe and a cooperating shoe movable between open and closed positions, an operator's station adjacent said track for application of garments to said ironers and removal of garments therefrom, a pair of relatively stationary cams mounted adjacent said track with one thereof at each side of said operator's station, said cams being in radially-spaced relationship and elongated generally in the direction of said track, a first pair of cam followers operatively associated with each of said ironers and mounted on said turntable for engagement with one of said stationary cams to be moved successively thereby from inoperative positions to operative positions, a second pair of cam followers operatively associated with each of said ironers and mounted on said turntable for engagement with the other of said stationary cams to be moved successively thereby from inoperative positions to operative positions, the cam followers of said first and second pair associated with each of said ironers being spaced

apart in the direction of rotary movement of the turntable a distance less than the length of the respective cams, engageable therewith, and ironer shoe operating mechanism associated with each of said ironers and including the associated pairs of cam followers, each of said operating mechanisms being responsive only to coincidental cam-imparted movements of both cam followers of one of said pairs from inoperative to operative positions to move their associated movable shoe in one direction, said operating mechanism being responsive only to coincidental cam-imparted movements of both cam followers of the other of said pairs from inoperative to operative positions to move their associated shoe in the opposite direction.

11. The structure defined in claim 5 in further combination with means mounting one of said relatively stationary cams for shifting movements into and out of the path of travel of its cooperating pair of cam followers, and manually-operated means for shifting said cam on said mounting means.

12. The structure defined in claim 10 in further combination with means mounting one of said relatively stationary cams for shifting movements radially of said track into and out of cam-engaging relationship with its cooperating cam followers, and manually-operated means for shifting said cam on said mounting means.

13. In an ironing machine of the class described, an endless track, a supporting structure mounted and guided for traveling movements about said endless track, driving mechanism for imparting movement to said supporting structure about said track, a normally open garment ironer mounted on said supporting structure and comprising cooperating pressing shoes mounted for relative movement between a normally open position and a closed position, a relatively stationary cam mounted adjacent said track and elongated generally in the direction thereof, first and second cam followers carried by the supporting structure for cam-imparted movements with respect thereto from normal inoperative positions to operative positions, said cam followers being spaced apart in the direction of travel of the supporting structure a distance less than the length of the cam and being located to be successively intercepted and moved by the cam from inoperative to operative positions, ironer shoe operating means mounted on the supporting structure, control means for said operating means, and operating mechanism for said control means, said operating mechanism comprising said cam followers and being responsive to coincidental cam-imparted movements of the cam followers from inoperative to operative positions, but to neither thereof singularly, to cause said ironers to be closed by said operating means.

14. In an ironing machine of the class described, an endless circular track, a supporting structure mounted and guided for travelling movements about said track, driving mechanism for imparting continuous and uninterrupted movement to said supporting structure about said track, a garment ironer mounted on said supporting structure, said garment ironer comprising a fixed shoe and a cooperating shoe movable between an open and closed position relative thereto, first and second cam followers carried by the supporting structure for movements with respect thereto from normal inoperative positions to operative positions, a relatively stationary cam mounted adjacent said track and

70

elongated generally in the direction thereof, said stationary cam lying in the path of travel of said cam followers whereby to successively intercept and move said cam followers from inoperative to operative positions, said cam followers being spaced apart in the direction of travel of said supporting structure a distance less than the length of the cam, ironer shoe-operating means mounted on the supporting structure for moving the movable shoe in one direction with respect to said stationary shoe, control means for said operating means, and operating mechanism for said control means, said operating mechanism including said cam followers and being responsive to coincidental cam-imparted movements of the cam followers from inoperative to operative positions, but to neither thereof singularly, to cause said movable shoe to be moved in one direction by said operating means.

15. In an ironing machine of the class described, an endless circular track, a supporting structure mounted and guided for travelling movements about said track, driving mechanism for imparting continuous and uninterrupted movement to said supporting structure about said track, a garment ironer mounted on said supporting structure, said garment ironer comprising a fixed shoe and a cooperating shoe movable between an open and closed position relative thereto, spaced pairs of cam followers carried by the supporting structure for movements with respect thereto from normal inoperative positions to operative positions, a pair of relatively stationary cams mounted adjacent said track and spaced apart in the direction thereof, said cams being elongated generally in the direction of said track and laterally offset from each other, each thereof lying in the path of travel of a different pair of said cam followers whereby to intercept and move said cam followers from inoperative to operative positions, the cam followers of each pair being spaced apart in the direction of travel of said supporting structure a distance less than the length of its cooperating cam, ironer shoe-operating means mounted on the supporting structure, control means for said ironer shoe-operating means, and operating mechanism for said control means and including said pairs of cam followers, said operating mechanism being responsive to coincidental cam-imparted movements of both cam followers of one of said pairs from inoperative to operative positions, but to neither thereof singularly, to cause said movable shoe to be moved in one direction by said operating means, said operating mechanism being responsive to coincidental cam-imparted movements of both cam followers of the other of said pairs from inoperative to operative positions, but to neither thereof singularly, to cause said movable shoe to be moved in the opposite direction by said operating means.

16. In an ironing machine of the class described, an endless track, a supporting structure mounted and guided for travelling movements about said endless track, driving mechanism for imparting movement to said supporting structure about said track, a normally open garment ironer mounted on said supporting structure and comprising cooperating pressing shoes mounted for relative movement between a normally open position and a closed position, a relatively stationary cam mounted adjacent said track and elongated generally in the direction thereof, first and second cam followers carried by the supporting structure for cam-imparted movements

75

with respect thereto from normal inoperative positions to operative positions, said cam followers being spaced apart in the direction of travel of the supporting structure a distance less than the length of the cam and being located to be successively intercepted and moved by the cam from inoperative to operative positions, fluid pressure-operated means mounted on the supporting structure for closing said ironer, a control valve for said fluid pressure-operated means, and operating mechanism for said control valve, said operating mechanism comprising said cam followers and being responsive to coincidental cam-imparted movements of the cam followers from inoperative positions, but to neither thereof singularly, to cause said fluid pressure-operated means to close said ironer.

17. In an ironing machine of the class described, an endless circular track, a supporting structure mounted and guided for travelling movements about said track, driving mechanism for imparting continuous and uninterrupted movement to said supporting structure about said track, a garment ironer mounted on said supporting structure, said garment ironer comprising a fixed shoe and a cooperating shoe movable between an open and closed position relative thereto, spaced pairs of cam followers carried by the supporting structure for movements with respect thereto from normal inoperative positions to operative positions, a pair of relatively stationary cams mounted adjacent said track and spaced apart in the direction thereof, said cams being elongated generally in the direction of said track and laterally offset from each other, each thereof lying in the path of travel of a different pair of said cam followers whereby to intercept and move said cam followers from inoperative to operative positions, the cam followers of each pair being spaced apart in the direction of travel of said supporting structure a distance less than the length of its cooperating cam, fluid pressure-operated means mounted on said supporting structure for moving said movable shoe to and away from pressing engagement with said relatively fixed shoe, a control valve for said fluid pressure-operated means, and operating mechanism for said control valve, said operating mechanism including said pairs of cam followers and being responsive to coincidental cam-imparted movements of both cam followers of one of said pairs, but to neither thereof singularly, to cause said fluid pressure-operated means to move said relatively movable shoe into pressing engagement with said relatively fixed shoe, said valve-operating mechanism being further responsive to coincidental cam-imparted movements of both cam followers of the other of said pairs, but to neither thereto singularly, to cause said fluid pressure-operated means to move said relatively fixed shoe away from pressing engagement with said relatively fixed shoe.

18. The structure defined in claim 16 in further combination with means mounting said relatively stationary cam for shifting movements into and out of cam-engaging relationship with said cam followers, and means for shifting said cam.

19. The structure defined in claim 16 in which said control valve operating mechanism further includes a lever carrying said second cam follower at one of its ends and pivotally mounted intermediate its ends to said supporting structure, a bellcrank carrying said first cam follower at one of its ends and having its intermediate

portion pivotally mounted to said lever intermediate the pivotal connection thereof to said frame and said second cam follower, the opposite end of said bell-crank having latching engagement with a portion of said supporting structure when said cam followers are in their inoperative positions and movable out of said latching engagement therewith upon movement of said first cam follower to its operative position by said relatively stationary cam, and a rigid link connecting the opposite end of said lever to said control valve.

20. In an ironing machine of the class described, an endless circular track, a supporting structure mounted and guided for travelling movements about said track, driving mechanism for imparting continuous and uninterrupted movement to said supporting structure about said track, a garment ironer mounted on said supporting structure, said garment ironer comprising a fixed shoe and a cooperating shoe movable between an open and closed position relative thereto, spaced pairs of cam followers carried by the supporting structure for movements with respect thereto from normal inoperative positions to operative positions, a pair of relatively stationary cams mounted adjacent said track and spaced apart in the direction thereof, said cams being elongated generally in the direction of said track and laterally offset from each other, each thereof lying in the path of travel of a different pair of said cam followers whereby to intercept and move said cam followers from inoperative to operative positions, the cam followers of each pair being spaced apart in the direction of travel of said supporting structure a distance less than the length of its cooperating cam, fluid pressure-operated means mounted on said supporting structure for moving said movable shoe to and away from pressing engagement with said relatively fixed shoe, a control valve, for said fluid pressure-operated means, a fluid pressure motor for operating said control valve, valve means controlling operation of said motor, and operating mechanism for said last mentioned valve means, including said pairs of cam followers and linkage connecting said

cam followers with said valve means, said operating mechanism being responsive to coincident cam-imparted movements of both cam followers of one of said pairs, but to neither thereof singularly, to cause said fluid pressure-operated means to move said relatively movable shoe into pressing engagement with said relatively fixed shoe, said operating mechanism being further responsive to coincident cam-imparted movements of both cam followers of the other of said pairs, but to neither thereof singularly, to cause said fluid pressure-operated means to move said relatively fixed shoe away from pressing engagement with said relatively fixed shoe.

15. 21. In an ironing machine of the class described, an endless track, a supporting structure mounted and guided for travelling movements about said endless track, driving mechanism for imparting movements to said supporting structure about said track, a normally open garment ironer mounted on said supporting structure and comprising cooperating pressing shoes mounted for relative movement between a normally open position and a closed position, relatively stationary actuating means mounted adjacent the track, first and second relatively movable actuated members carried by the supporting structure for movements with respect thereto from normal inoperative positions to operative positions, said actuated members being located to be intercepted and moved by the actuating means from inoperative to operative positions, an ironer shoe operating mechanism mounted on the supporting structure, said operating mechanism comprising said actuated members and being responsive only to coincidental actuated movement of said actuated members for closing the ironer.
